UNITED STATES PATENT OFFICE

GROSVENOR N. ALLEN, MARY G. PARKER, AND SETH H. LEAVENWORTH, OF ONEIDA, NEW YORK, ASSIGNEES TO ONEIDA COMMUNITY, LIMITED, OF ONEIDA, NEW YORK, A CORPORATION OF NEW YORK

DESIGN FOR A POT OR SIMILAR ARTICLE

Application filed November 6, 1931. Serial No. 41,646. Term of patent 14 years.

To all whom it may concern:

Be it known that we, GROSVENOR N. ALLEN, MARY G. PARKER, and SETH H. LEAVENWORTH, citizens of the United States, residing at Oneida, county of Madison, State of New York, have invented a new, original, and ornamental Design for a Pot or Similar Article, fully described and represented in the following specification and the accompanying drawings forming a part of the same, in which Figure 1 is a side elevation of the pot showing our new design and Figure 2 is a cross-section thereof on the line 2—2 of Figure 1, the essential feature being the ornamentation on both sides of the body of the pot or similar article.

We claim:

The ornamental design for a pot or similar article as shown and described.

In testimony whereof we have hereunto set our hands.

GROSVENOR N. ALLEN.
MARY G. PARKER.
SETH H. LEAVENWORTH.
